(57) **CLAIM**

The ornamental design for a fragrance diffuser bottle, as shown and described.

DESCRIPTION

FIG. 1 is a front elevational view of a first embodiment of fragrance diffuser bottle, embodying my new design, the rear elevational view being identical thereto;

FIG. 2 is a left side elevational view thereof, the right side elevational view being identical thereto;

FIG. 3 is a top plan view thereof;

FIG. 4 is a bottom plan view thereof;

FIG. 5 is a front perspective view thereof;

FIG. 6 is a front elevational view of a second embodiment of a fragrance diffuser bottle, embodying my new design, shown with an unclaimed wick, wick holding ring and fluid level, the rear elevational view being identical thereto;

FIG. 7 is a front perspective view thereof;

FIG. 8 is a front elevational view of a third embodiment of a fragrance diffuser bottle, embodying my new design, shown with an unclaimed wick, wick holding ring, cap and fluid level, the rear elevational view being identical thereto; and, FIG. 9 is a front perspective view thereof.

The broken line showing of the bottle neck, threads, wick, wick holding ring, cap and fluid level are included for the purpose of illustrating unclaimed portions of the article and form no part of the claimed design.
